UNITED STATES PATENT OFFICE.

THOMAS D. WEST AND GEORGE MULLIGAN, OF SHARPSVILLE,
PENNSYLVANIA.

RAILWAY-FROG.

SPECIFICATION forming part of Letters Patent No. 684,020, dated October 8, 1901.

Application filed April 29, 1901. Serial No. 57,950. (No model.)

To all whom it may concern:

Be it known that we, THOMAS D. WEST and GEORGE MULLIGAN, residents of Sharpsville, Mercer county, State of Pennsylvania, have 5 invented certain new and useful Improvements in Railway-Frogs; and we do hereby declare the following to be a full, clear, and exact description of the invention, such as will enable others skilled in the art to which it pertains to make and use the same.

Our invention relates to improvements in railway-frogs, avoiding objectionable breaks, centrally of the frog, in the intersecting rails of the through or main and the side tracks 15 and avoiding destructive pounding or hammering and wear upon the rail-sections of the frog and wear upon the wheels of the rolling-stock.

The primary object of this invention is to 20 improve the construction of a frog of the character indicated, so that the frog is rendered more durable and reliable and so that the frog can be readily kept in a clean and serviceable condition in all kinds of weather.

Another object is to render a frog of the 25 character indicated safer than heretofore, and, in fact, to reduce to a minimum the liability to accidents.

With these objects in view our invention 30 relates to certain peculiarities of construction and combinations of parts hereinafter described, and pointed out in the claims.

In the accompanying drawings, Figure I is a top plan of portions of a through or main 35 track and side track and a frog embodying our invention, and this figure is also illustrative of the operative connection of the shiftable rail-section of the frog with the mechanism for operating the switch-rails for 40 switching rolling-stock from the main track onto the side track. Fig. II is a top plan of our improved frog, and portions are broken away and in section in this figure to more clearly show the construction. The parts 45 illustrated in this figure are shown on a larger scale than in Fig. I. Fig. III is a vertical section in detail, showing portions of the frog on line III III, Fig. II, looking in the direction indicated by the arrow. Fig. IV is a 50 vertical section showing portions of the frog on line IV IV, Fig. II, looking in the direc-

tion indicated by the arrow. Fig. V is a vertical section showing portions of the frog on line V V, Fig. II, looking in the direction indicated by the arrow. 55

Referring to Fig. I of the drawings, *a* designates a through or main railway-track; *b*, a side track leading to one side of the main track; *c*, the switch-rail section of the side track, and *d* the switch-rail section of the 60 main track.

Our improved frog comprises a laterally swingable or shiftable rail-section *e*, arranged centrally of the frog at the intersection of those rails of the tracks *a* and *b* in the formation of which the remaining rail-sections of the frog participate, and the said rail-section *e* is arranged to form a portion of the main track or a portion of the side track, according as the said rail-section *e* is swung or 65 shifted laterally in the one direction or the other. 70

Our improved frog comprises also two rail-sections *c'* and *d'*, which are arranged in close proximity to the sweep of the rail-section *e* 75 and extend and diverge from one end of the said rail-section *e* toward and are arranged in line with the switch-rails *c* and *d*, respectively, which rails *c* and *d* form portions of the side track and main track, respectively, as already 80 indicated, and are arranged between the remaining rails of the said tracks in the usual manner and diverge, therefore, from the frog-rail sections *c'* and *d'* and are operatively connected, near their farther separated ends, with 85 the switch-operating rod *f* by means of a link *g*, which is arranged between and parallel with two of the ties *t*, to which the tracks and the frog are secured in any approved manner, and extends from the main track to the side 90 where the side track leads from the main track, and the rod *f* is operatively connected in the usual manner with a crank *h'* of the switch-operating crank-shaft *h*, which is arranged parallel with and a suitable distance 95 from the main track and is provided with a lever *h* for operating the shaft. The switch-rails *c* and *d* are attached to the connected frog-rail sections *c'* and *d'* by straps *j*, secured to the said rail-sections in any approved 100 manner.

Our improved frog comprises also two rail-

- sections a' and b' , which are arranged in line with the rail-sections d' and c' , respectively, and a suitable distance from the last-mentioned sections and extend into close proximity to the sweep of the rail-section e . The frog-rail sections c' and d' , as already indicated, diverge from one end of the rail-section e , and the frog-rail sections a' and b' diverge from the other end of the said rail-section e .
- 10 The rail-sections a' and b' form portions of the main track a and side track b , respectively. The rail-sections a' and b' meet each other adjacent to the rail-section e and are cut away and fitted or welded together at 15 their contiguous ends, so that they both terminate at the adjacent end of the rail-section e .

As already indicated, the rail-section e is capable of being swung or shifted laterally, 20 and the arrangement of parts is such that the said rail-section e shall be arranged in line with the frog-rail sections b' and c' and extend between the opposing ends and close to the said rail-sections b' and c' or shall be arranged 25 in line with the frog-rail sections a' and d' and extend between and close to the opposing ends of the said rail-sections a' and d' , according as the said rail-section e is actuated laterally in the one or the other direction.

30 The rail-sections a' and b' of the frog are rigidly secured in any approved manner to a plate k , which is rigidly secured to the horizontally-arranged base-forming plate l of the frog. The base l rests upon and extends over 35 and is suitably secured to several of the ties t . The plate k constitutes a raised portion of the base l .

The rail-sections c' and d' of the frog are rigidly secured in any approved manner to 40 a plate m , which is rigidly secured to and constitutes a raised portion of the said base l . The rail-section e rests upon and is rigidly secured in any approved manner to a plate o , which extends between the plates or raised 45 portions k and m of the base l and is pivoted vertically, as at o' , near the meeting ends of the frog-rail sections a' and b' to the said base, so that the said plate o is capable of being swung in a horizontal plane upon the 50 said base, between the plates or raised portions k and m of the base. The pivot o' extends, preferably, into the rail-section e . The plate o has its opposite ends extending into close proximity to the plates or raised 55 portions k and m of the base l , and the opposing edges of the said plates or raised portions k and m extend circumferentially of the axis of the plate o to accommodate the extension of the said plate o and the rail-section e upon it into close proximity to the said plates or raised portions of the base without interfering with the shifting of the said intermediate plate o upon its axis to bring the rail-section thereon into line with the frog-rail sections a' and d' , as shown in Fig. I, or 60 into line with the frog-rail sections b' and c' , as shown in Fig. II, according as the said

intermediate plate o , with the rail-section thereon, is actuated in the one direction or the other.

The plate o , and consequently the rail-section e upon it, is operatively connected with the switch-operating shaft h , and the mechanism employed in establishing operative connection between the said parts comprises, preferably, an arm o^2 , which is rigidly secured to the upper side of the plate o and projects laterally of the said rail in the direction of the aforesaid shaft, as shown more clearly in Fig. II, and the arm o^2 is operatively connected by a link o^3 with one end of a bar p , which extends in under the outer rail of the side track b and is arranged between and longitudinally of two of the ties t and has its other end connected by a rod p' with the crank h^3 of the shaft h . Suitably-applied guides p^2 retain the bar p parallel with the said ties and prevent displacement of the said bar laterally between the said ties. The link o^3 extends through a strap or 85 ear l' , with which the base o is provided. The arm o^2 , as shown very clearly in Figs. II and 90 V, is attached to the link o^3 by a vertical pin r , which extends through the link o^3 and is screw-threaded externally at its lower end 95 (see Fig. V) and screwed into a correspondingly-threaded hole o^4 , formed in the said arm o^2 . The pin r at its upper end has a flange r' overlapping the upper side of the arm o^2 and secured to the said arm o^2 by a 100 screw r^2 , and the flange r' , formed on the pin r and secured to the arm o^2 , obviously prevents loosening of the pin.

By the construction hereinbefore described it will be observed that the rail-section e of 105 the frog and the switch-rail sections c and d of the side and main tracks are simultaneously operated by a proper manipulation of the operating-lever h^2 and that the said rail-section e of the frog forms a portion of the 110 side track or a portion of the main track, according as the switch-rail section of the side track or the switch-rail section of the main track is rendered operative. When the frog-rail section e forms a portion of the main 115 track, as shown in Fig. I, the switch-rail section d of the said track is in an operative position, and, obviously, when the rail-section e is shifted to form a portion of the side track, as shown in Fig. II, the switch-rail section c of the side track becomes operative. 120

Means for limiting the movement of the rail-section e of the frog is provided, and the means employed for limiting the movement of the said rail-section e in the direction of the 125 operating-shaft comprises, preferably, a plate or block s , which is rigidly secured to the outer side of the web of the frog-rail section d' and projects a suitable distance beyond the inner end of the said rail-section d' , as 130 shown very clearly in Figs. II and V, and has the arrangement required to render it capable of being engaged and form a stop for the rail-section e of the frog when the said rail-

- section *e* is actuated into line with the rail-sections *c'* and *d'* of the frog. The means for limiting the actuation of the rail-section *e* of the frog in the opposite direction—that is, in the direction in which the said rail-section is shifted during the actuation of the same into line with the frog-rail sections *b'* and *c'*—comprises, preferably, a plate or block *u*, which is rigidly secured to the outer side of the web 5 of the frog-rail section *c'*, as shown in dotted lines, Fig. II, and in solid lines, Figs. IV and V, and projects beyond the inner end of the said rail-section *c'* in position to be engaged by the adjacent side of the web of the rail-section *e* when the said rail-section *e* has been brought into line with the side-track frog-rail sections *c'* and *d'*.
- Means for preventing upward displacement of the pivoted end of the plate *o* is provided 10 and (see Figs. II and III) comprises, preferably, two plates or blocks *w* and *w*, rigidly secured to the base *l* at opposite sides, respectively, of the sweep of the plate *o*, adjacent to or near the pivoted end of the said plate *o* and having inwardly-projecting flanges *w'* overlapping the upper side of the said plate *o*, which flanges *w'* are long enough 15 to overlap the plate *o* in either position of the said plate *o*.

- 20 Means for preventing displacement of the plate *o* upwardly near the opposite or free end of the plate *o* is provided and comprises, preferably, two plates or blocks *x* and *y*, rigidly secured to the plate or raised portion *m* 25 of the base *l* and projecting beyond the inner end of the said plate or raised portion *m* and overlapping the upper side of the sweep of the plate *o*. The plate or block *x* (see Figs. I, II, IV, and V) is secured to the plate 30 or raised portion *m* at the outer side of the side-track frog-rail section *c'* and is arranged to overlap the upper side of the plate *o* when the said plate *o* is in position with the rail-section *e* thereon in line with the side-track frog-rail sections *b'* and *c'*.

The plate or block *y* (see Fig. II) is preferably interposed between the frog-rail sections *c'* and *d'*, which are preferably cut away at the base to more satisfactorily accommodate the said location of the said member *y*. The plate or block *y* overlaps the upper side of the plate *o* in either position of the said plate *o*; but the rail upon the said plate *o* is cut away at the base, as at *e'*, (see Fig. IV,) to 55 accommodate the aforesaid location of the said member *y*.

It will be observed that our improved construction of frog renders it conveniently cleanable and maintainable in a clean and working condition, because any matter lodging upon the base *l*, between the raised portions *k* and *m* of the base, can be readily swept from the base as there are no pockets or recesses formed in the base for catching such matter. It will be observed also that our improved frog is exceedingly simple and dur-

able in construction, reliable in its operation, and not liable to get out of order.

We would here remark that the plates or blocks *w* are gradually reduced in width, as 70 at *w'*, (shown by dotted lines, Fig. II,) below their flanges *w'*, in the direction of the sweep of the shiftable rail-section, so that the space below the said flanges *w'* can be readily kept clear of obstructing matter blown or otherwise deposited thereunder. We would remark, furthermore, that the plates or blocks *s* and *u* are instrumental in preventing tipping or lateral displacement of the movable rail-section *e*; but to more positively prevent 80 tipping or lateral displacement of the said rail-section we have provided two plates or blocks *a'* and *b'*, rigidly secured in any approved manner to the rail-sections *a'* and *b'* by bolts or screws *a* and *b*, as shown in Figs. 85 II, III, and IV, and overlapping opposite sides, respectively, of the web of the rail-section *e*, between the axis of the said rail-section and the rail-sections *a'* and *b'*.

It will be observed that the stationary base 90 *l* has no holes or recesses forming receptacles for dust, dirt, accumulation of ice, &c., at the upper surface of the said base between the raised portions *k* and *m* thereof and can be readily kept clear of obstructing matter because the movable section of the frog rests upon the said surface and the space formed between the raised portions *k* and *m* has its bottom flush with the upper surface of the base *l* at the sides of the said space, so that 100 the path in which the base *o* of the said frog-section operates is not closed at the sides and the upper surface of the base *l* under and adjacent the said path can easily be kept swept clean at all times. Also the cutting away to 105 a point, as at *w'*, of the inner ends of the blocks *w* below their flanges *w'* is important to prevent the accumulation of obstructing matter under the said flanges.

What we claim is—

1. A railway-frog, comprising a stationary base *l* having two raised portions *k* and *m* arranged a suitable distance apart longitudinally of the frog so as to form, between the said raised portions, a space which is open at 115 the sides and has its bottom flush with the upper surface of the base at the sides of the said space, a laterally-swingable frog-section arranged upon the base and longitudinally of the frog between the said raised portions 120 *k* and *m* of the base; two stationary rail-sections *a'* and *b'* arranged upon and rigid with the raised portion *k* of the base and diverging from one end and in close proximity to the aforesaid movable frog-section, and two 125 stationary rail-sections *d'* and *c'* upon and rigid with the raised portion *m* of the base at the other end of the said movable frog-section and extending into close proximity to and diverging from the said last-mentioned 130 frog-section and arranged in line with the different first-mentioned stationary rail-sec-

tions, respectively, and the arrangement of parts being such that the aforesaid shiftable frog-section shall be in line with the rail-sections b' and c' , or in line with the rail-sections 5 a' and d' , according as it has been shifted into the one or the other of its positions.

2. A railway-frog comprising a base l having two raised portions k and m arranged a suitable distance apart longitudinally of the 10 frog so as to form between the said raised portions a space which is open at the sides and has its bottom flush with the upper surface of the base at the sides of the said space; a plate o arranged upon the base and longitudinally of the frog within the aforesaid space and vertically pivoted to the base; means for swinging or shifting the said plate o laterally upon the base; a rail-section e upon and extending longitudinally of and 15 rigid with the said plate; two stationary rail-sections a' and b' upon and rigid with the raised portion k of the base and diverging from one end of and extending into close proximity to the rail-section e , and two stationary rail-sections d' and c' upon and rigid with the raised portion m of the base at the other end of the said rail-section e and extending into close proximity to and diverging from the said last-mentioned rail-section and 20 arranged in line with the different first-mentioned stationary rail-sections, respectively, and the arrangement of parts being such that the rail-section e shall be arranged in line with the rail-sections b' and c' or in line with 25 the rail-sections a' and d' according as the aforesaid pivoted plate has been shifted into the one or the other of its positions.

3. A railway-frog comprising a base l ; a laterally-swingable frog-section resting upon the 30 base and having its axis near one end thereof, and provided, at its other end, with a laterally-projecting arm o^3 ; mechanism for swinging or shifting the said movable frog-section upon its axis and comprising a link o^3 and an externally-screw-threaded pin r extending downwardly through the said link and screwed into the aforesaid arm and having a flange r' overlapping and secured to the said arm at one side of the pin; two stationary rail-sections 35 a' and b' mounted upon and rigid with the base and diverging from one end of and extending into close proximity to the aforesaid shiftable frog-section, and two stationary rail-sections d' and c' mounted upon and rigid with the base at the other end of the said shiftable frog-section and extending into close proximity to and diverging from the said last-mentioned frog-section and arranged in line with the different first-mentioned stationary 40 rail-sections, respectively, all arranged and operating substantially as shown, for the purpose specified.

4. A railway-frog comprising a base l ; a plate o resting upon the base and pivoted to the base vertically near one end thereof and provided, at its other end, with a laterally-projecting arm o^2 ; mechanism for swinging 45

or shifting the said plate upon its axis and comprising a link o^3 and an externally-screw-threaded pin r extending downwardly through the said link and screwed into the aforesaid arm and having a flange r' ; a screw e^2 securing the said flange to the aforesaid arm; a rail-section e arranged upon and longitudinally of and rigidly secured to the said plate o ; two stationary rail-sections a' and b' mounted upon and rigid with the base and diverging from one end of and extending into close proximity to the rail-section e , and two stationary rail-sections d' and c' mounted upon and rigid with the base at the other end of the said rail-section e and extending into close proximity to and diverging from the said last-mentioned rail-section and arranged in line with the different first-mentioned stationary rail-sections, respectively, all arranged and operating substantially as shown, for the purpose specified.

5. A railway-frog comprising a base l having two raised portions k and m arranged a suitable distance apart longitudinally of the frog so as to form, between them, a space which is open at the sides and has its bottom flush with the upper surface of the base at the sides of the said space, a plate o resting upon the base within the aforesaid space and pivoted to the base so as to render the said plate capable of being swung or shifted in a horizontal plane; means for swinging or shifting the said plate; two plates or blocks w and w rigid with the base at opposite sides, respectively, of the sweep of the aforesaid plate o and having flanges w' overlapping the said sweep, which plates or blocks w have their inner ends reduced in width below their flanges and in the direction of the sweep of the aforesaid plate o ; a rail-section e arranged upon and longitudinally of and rigidly secured to the said plate o ; two stationary rail-sections a' and b' upon and rigid with the raised portion k of the base and diverging from one end of and extending into close proximity to the rail-section e , and two stationary rail-sections d' and c' upon and rigid with the raised portion m of the base at the other end of the said rail-section e and extending into close proximity to and diverging from the said last-mentioned rail-section and arranged in line with the different first-mentioned stationary rail-sections, respectively, all arranged and operating substantially as shown, for the purpose specified.

6. A railway-frog comprising a base l having two raised portions k and m arranged a suitable distance apart longitudinally of the frog so as to form, between them, a space which is open at the sides and has its bottom flush with the upper surface of the base at the sides of the said space; a plate o resting upon the base within the aforesaid space and pivoted to the base so as to render the said plate capable of being swung or shifted in a horizontal plane; means for swinging or shifting the said plate; two plates or blocks w and w

w rigid with the base at opposite sides, respectively, of the sweep of the aforesaid plate o and having flanges w' overlapping the said sweep; a rail-section e arranged upon and 5 longitudinally of and rigidly secured to the said plate o; two stationary rail-sections a' and b' upon and rigid with the raised portion k of the base and diverging from one end of and extending into close proximity to the rail-section e; two stationary rail-sections d' and c' upon and rigid with the raised portion m of the base at the other end of the said rail-section e and extending into close proximity to and diverging from the said last-mentioned 10 rail-section and arranged in line with the dif- 15

ferent first-mentioned stationary rail-sections, respectively; a stationary plate or block y interposed between the frog-rail sections c' and d' and overlapping the sweep of the plate o, and the rail-section e being cut 20 away at the base, as at e', to accommodate the location of the aforesaid member y.

Signed by us at Sharpsville, Pennsylvania, this 25th day of April, 1901.
